UNITED STATES PATENT OFFICE.

JAMES E. KANE, OF CANTON, OHIO, ASSIGNOR OF ONE-HALF TO CHARLES A. STREB, OF CANTON, OHIO.

SCRAPER FOR TINNING MACHINES.

Application filed March 15, 1923. Serial No. 625,326.

To all whom it may concern:

Be it known that I, JAMES E. KANE, a citizen of the United States, residing at Canton, in the county of Stark and State of Ohio, have invented certain new and useful Improvements in Scrapers for Tinning Machines, of which the following is a specification.

This invention relates to scrapers for tinning machines and has for its objects to provide means for obtaining uniformity in the thickness of the metal coating applied upon the faces of the sheets, thus not only producing a better and more uniform coating upon the sheet, but also effecting a saving in the tin or other coating metal used.

The above and other objects may be obtained by constructing the device in the manner illustrated in the accompanying drawings, in which—

Figure 1 is a fragmentary, longitudinal, sectional view through a tinning machine, showing the improved scraper applied thereto;

Fig. 2, a side elevation of a portion of the tinning machine; and

Fig. 3, a sectional view through one wall of the tinning machine, showing the gearing.

Similar numerals of reference indicate corresponding parts through the drawings.

A tinning machine of usual construction is illustrated at 1, the sheets being arranged to be fed into one end of the tinning machine between the upper and lower guiding aprons 2 and 3 to the pairs of delivery rolls 4—4 and 5—5.

The guiding aprons 2 and 3 may be connected to the opposite side walls of the tinning machine in any usual and well known manner. For the purpose of providing an even and uniform coating upon the faces of the sheets, as they pass through the tinning machine, scrapers are mounted at the upper ends of the aprons and arranged to engage opposite faces of the sheets as they pass therethrough to scrape off the surplus coating metal from the faces of the sheets, leaving a smooth, even coating of proper thickness upon each face of the sheet.

The lower apron 3 is provided with a

scraper comprising the angular plate 10 mounted upon the spring arms 11, connected at their lower ends to the lower apron, 55 the plate 10 having the inwardly and upwardly disposed, angular flange 12, the straight inner edge 13 thereof normally extending slightly over the path of a sheet, passing from the tin pot to the delivery 60 rolls 4—4. The inner scraper comprises a roll 14 arranged to rotate in a direction opposite to the movement of the sheet C.

As shown in Fig. 2, each of the lower delivery rolls 4 has a gear 15 mounted thereon, said gears meshing with each other to drive the rolls in the direction of the arrows. The right hand roll 4 has a pinion 16 fixed thereon meshing with a pinion 17 upon the roll 14 to drive the roll 14 in the 70 direction of the arrow.

The upper delivery rolls 5 are similarly geared together by means of the gears 18. At the opposite end of the tinning machine, a large gear 19 is fixed upon the shaft of 75 the right hand delivery roll 4 and a similar gear 20 upon the shaft of the left hand delivery roll 5, these gears meshing with each other and a drive gear 21 meshing with the gear 20 to drive all of the rolls in the directions of the arrows shown in Fig. 2.

As the sheet shown at C passes through the tinning machine and upward through the guide apron into the lower delivery rolls 4—4, the upper edge of the sheet will 85 first engage the roll 14, the inner face of the sheet passing over the roll which operates in the opposite direction, and removes the surplus tin from the sheet, smoothing the inner face, while the outer side of the sheet engages the edge 13 of the scraper 10, as illustrated in Fig. 1, this scraper removing the surplus coating of tin from the outer side of the sheet.

I claim:—

1. In combination with a tinning machine provided with a guiding apron and delivery rolls, a roller located between the apron and delivery rolls and arranged to engage the forward face of a sheet as it 100 passes from the apron to the delivery rolls, means for rotating the roller in a direction opposite to the movement of the sheet, a scraper adapted to extend over one lip of

the apron to engage the rear surface of the sheet and spring arms connecting the scraper to the apron.

2. In combination with a tinning machine provided with a guiding apron and delivery rolls, a roller located between the apron and delivery rolls and arranged to

engage the adjacent face of a sheet as it passes from the apron to the delivery rolls, and means for rotating the roller in a direction opposite to the movement of the sheet. ¹⁰

In testimony that I claim the above, I have hereunto subscribed my name.

JAMES E. KANE.
